UNITED STATES PATENT OFFICE.

WILL R. GEARY, OF HORNELL, NEW YORK.

METHOD OF AND APPARATUS FOR FORMING SPEAR POINTS ON GLOVES.

Application filed April 27, 1923. Serial No. 635,053.

This invention relates to improvements in machines for making what has become known in the glove art as spear points.

On the back of gloves are several longitudinally disposed cords, made in various ways with stitching machines, to lend beauty and style to the gloves. To lend further style and beauty to the glove backs, manufacturers have added to the cords short angular 10 cords or legs disposed on opposite sides of the main cords to form what has now been recognized as spear points. As these angular short stitches forming the spears are disposed some distance from the terminals of 15 the main cords, the latter have to be completed, and subsequently the glove material moved or adjusted under the presser foot to first stitch one side of a spear, then again release and adjust the material and form 20 the opposite side of the spear.

In the formation of the opposite angular stitches in the production of the spears, the operator guesses at the alignment and the number of stitches necessary to complete 25 the legs of the spear, with the result that even where expert operators are employed, the angular disposition of the various spears differ and the number of stitches in the respective spear legs, or the stitches between 30 any two spears differ. Under these circumstances the finished product is not satisfactory and results in what may be termed inferior workmanship.

The object of the invention is to provide 35 a machine and method, wherein an operator can accurately locate a glove back beneath a presser foot and guide to stitch the respective legs forming the spear point at the same angle with respect to the cord to which 40 they are attached, and at the same time construct these respective legs of the spear point of the same number of stitches by automatically limiting the stitching operation of the machine to a predetermined number of 45 stitches in each instance.

The invention contemplates the use of a 50 guide which may constitute the presser foot, which is provided with an edge having that angularity with respect to the line of stitching as is contemplated for the angularity of the leg of the spear with respect to the cord, the angularly related edge of the guide being that distance from the needle opening in 55 such guide or presser foot which is designed for the length of the spear point leg, so that with a cord aligned with the inclined edge

of the guide, the particular spear point leg being formed will be started a distance from that cord equal to the distance of the inclined edge of the guide from the needle 60 hole in the guide in the line of stitch. Thus with the glove arranged to position the particular cord in line with the inclined edge of the guide, the predetermined number of 65 stitches permitted by the automatic control mechanism of the sewing machine will stitch a spear point from the starting point on the glove, beneath the needle hole of the guide, to the cord which is aligned with the guide. The second position of the glove back for 70 the second leg of the particular spear is provided for by adjusting the previously aligned cord the proper angle to the inclined edge of the guide and the juncture of the previously formed spear leg and that cord beneath 75 the needle hole of the guide. Thus the guide serves to cooperate with the cord to which the spear point is being applied in both instances, that is, in forming both legs of the particular spear point, and the spear 80 point as an entirety starts at the free terminal of one leg and ends at the free terminal of the other leg, one spear point being stitched toward the cord and the other from the cord. 85

The invention also comprehends the utilization of the guide as a means for providing an additional leg or more than one to the two-leg spear point, this being particularly desirable where the cords are of double form 90 as indicated in Figs. 14 and 15. For this purpose, by arranging the cord terminal substantially at the inclined edge of the guide in the line of stitching with one of the legs of the previously formed spear point at 95 right angles to said guide, the third leg of the spear point will be stitched in line with the cord and will be started at the proper distance from the end of said cord, as the 100 cord is in a position for starting which defines the length of the spear leg being stitched and also its direction.

The uniformity of angularity of the spears and the respective legs of the spears being formed of exactly the same number of 105 stitches results in the production of glove backs having all the spear points exactly alike, and further results in a neat and carefully worked out design on the glove.

In order that each of the legs of all the 110 spears shall have the same number of stitches, it is absolutely essential that means

be provided to automatically stop the stitching mechanism immediately the desired stitches have been formed, and yet provide means for permitting manual operation of the stitching mechanism after the machine has been stopped to permit mending or adding stitches, if found desirable or necessary. Therefore, it is one of the objects of this invention to provide means for automatically disconnecting the power from the stitching mechanism and immediately applying a brake to reduce the momentum of the parts after the power has been disconnected, and thereafter free the stitching mechanism from the stopping mechanism and leave it free to be manually operated, without in any way affecting the power driven means.

The invention also comprehends improvements in the details of construction and arrangement of parts which will be hereinafter described and particularly pointed out in the claims.

In the drawings:

Figure 1 is a perspective view of my improvement shown applied to a Singer "cord" machine.

Figure 2 is an end view of the same, showing the parts in normal position in full lines.

Figure 3 is a sectional view of the attachment, showing the parts in operative relation when stitching.

Figure 4 is a similar view but showing the power disconnected, and the brake applied.

Figure 5 is a similar view but showing the parts in normal position.

Figures 6 and 7 are views of the clutch members and the shiftable element.

Figure 8 is a view of the lower end of the arm and the buffer.

Figure 9 is a detail perspective view of the presser foot.

Figure 10 is a view illustrating the first position of the material under the presser foot to form one leg of a spear.

Figure 10^a is a similar view showing the position of the parts after completion of the first leg of the spear.

Figure 11 is a similar view showing the material shifted and re-located to form the second leg of a spear.

Figure 11^a is a similar view but showing the position of the material when the spear is completed.

Figure 12 is a plan view of slightly different form of presser foot.

Figure 13 is a view of another form of presser foot.

Figures 14 and 15 are diagrammatic views showing how double spear points may be made.

In the drawings, 1 indicates a Singer sewing machine of the type for forming cords on the backs of gloves. This machine embodies the usual stitch forming mechanism,

including in this instance a pair of needles 2, and associated therewith a pressure foot 3. The presser foot as shown is made in two parts 4 and 5, the part 4 being attached to the usual vertical post 6, mounted in the head of the machine, while the part 5, is pivoted at 7, to the toe of the part 4. The part 5 forms the foot proper and is provided with ears 8, through which the pivotal connection 7 passes, the pivot being so located as to permit of a slight rocking movement of the part 5 when the glove material is inserted. The front edge of the foot is angular, as at 10, to form a visible guide in making the spear points, while in rear of the front edge is an elongated opening 10^a for passage of the needles. In addition to this function, the opening is used as a means for sighting a point on the glove for starting the first leg of a spear, as well as sighting the finished end of the leg to ascertain if same has had stitches enough to reach the cord.

The presser foot may have its front edge bevelled in opposite directions to form two visible guides in the formation of the spears, as shown in Figures 12 and 13. These edges 11 and 12 may come to a point in front of the foot as shown in Figure 13, or the edges 13 and 14 may extend inwardly and terminate at a point in rear of the front, as shown in Figure 12. Obviously, an ordinary rigidly formed presser foot could be employed in lieu of the two part structure described.

Cooperating with the visible guide are means to determine the number of stitches worked in a spear point, and means for effectively stopping the stitching mechanism with the needle up and out of the material and above the presser foot to leave the opening 10^a unobstructed to enable the operator to view the cord to start the stitching in the next operation.

On the shaft 15 of the sewing machine, and fitting over the bearing projecting from the head is the cupped end 16, of a stub shaft 17, the two shafts being pinned together at 18. Fastened on the cup end of the stub shaft is the usual hand or balance wheel 19, and adjacent thereto is fastened one member 20 of a positive clutch 21. This member is recessed at 22, and at the edges, it is provided with a series of teeth 23. Slidably mounted on the stub shaft is a shiftable element which is formed at one end with a clutch member 24, at its opposite end with a clutch member 25 and intermediate the clutch members with a pinion 26. The clutch member 24 is recessed on one face as at 27, and on its edge it is provided with a series of teeth 28, this member and the member 20 constituting the clutch 21. Housed in the recesses 22 and 27 is a spring 29, the tension of which tends to normally hold

the two members apart and consequently the teeth 28 out of engagement with the teeth 23. The clutch member 25 cooperates with a clutch member 30, and forms with the latter a friction clutch 31. The member 30 is formed on a pulley 32, which is loosely mounted on the stub shaft 17, and integral with this pulley is a hub which is provided with a groove 33 to receive a clutch shifter 34.

The flange on the loose pulley which forms the clutch member 30 is bevelled on its periphery, as shown at 35, while the clutch member 24 is correspondingly bevelled as at 36, but in the opposite direction as shown in Figure 3.

The outer end of the stub shaft 17 is mounted in a bearing formed in a bracket 37, and a spring 38, interposed between the two clutch members 25 and 30, tends to normally slide the loose pulley toward the bearing and separate the clutch engaging surfaces.

The numeral 40 indicates an arm provided at its upper end with a bearing opening 41, which receives the hub 42 of the clutch member 20. The hub rotates in the bearing in the arm but the latter is hung on the hub and depends therefrom. The lower end of the arm is provided with oppositely disposed pins which operate in guides formed in a housing 44 arranged on the table supporting the sewing machine. Buffer springs 44^a are interposed between the arm and the ends of the housing, the tension of the springs being equal so as to hold the arm in a predetermined normal position.

Extending from and fixed to the arm 40, is a stub shaft 45 and to the outer end of the latter is fastened the bracket 37. Mounted to rotate on the stub shaft 45 is a gear wheel 46, which meshes with the pinion 26. On opposite faces of the gear wheel are lugs 47 and 48, the lug 47 being positioned and bevelled on one face to engage with the bevelled periphery 36, of the clutch member 24, while the lug 48 is positioned and bevelled to engage with the bevelled periphery 35 of the clutch member 30. Mounted in one face of the lug 48 is an anti-friction roller 49, designed to reduce friction when in cooperative relation with the bevelled periphery 35, as will be explained later on. A spring 50 has one end made fast at 51 to the gear wheel, and is then coiled around the stub shaft and has its opposite end fastened to the arm 40 as shown at 52. The tension of this spring is such as to normally bring an adjustable stop 53 up against a fixed abutment 54, or if desired, the location of the stop and abutment may be reversed. As shown, the adjustable stop may be engaged in any one of a series of openings 55 in the gear wheel 46.

The pinion makes one complete revolution in the formation of one stitch, and the teeth of the gear wheel are multiples of the teeth

of the pinion so as to predetermine the number of stitches. In connection with this ratio of teeth, the operator can determine the number of stitches the stitching mechanism will produce by adjusting the position of the stop 53.

Assuming the parts are in their normal position as shown in Figures 1 and 2. That is to say, the clutches 21 and 31 are disengaged, and the adjustable stop 53 is up against the fixed abutment 54, which positions the needle above the presser foot. The operator now takes the glove back on which the cords have been worked and passes it under the presser foot with the cord, as *a*, to which the spear points are to be connected in line with the edge 10 of the guide. The line of stitching indicated at *b*, is thus at an angle to the cord *a*, and this angle is the predetermined angle of the particular spear point leg being formed to the cord. Furthermore, the distance between the needle and sighting opening 10^a in the guide to the cord *a*, is the usual length of the leg of the spear point, that is, the length determined by the number of stitches permitted by the automatic control mechanism hereinbefore described. Having completed the stitching of this leg, the final stitches will be at or on the cord. While sighting the guide, the operator also sights a point on the glove through the opening 10^a to properly locate the material where the needles are to begin the stitches in the formation of the spear leg.

The distance between the edge 10 of the presser foot and the center of the opening therein is the same or about the same as the length of a leg of a spear, so as to insure of the last stitch terminating on the cord. The proper position of the glove back having been obtained, the presser foot is lowered, then the operator applies pressure to the treadle 60, and through suitable connections, such as shown at 61, the clutch shifter 34 is actuated, which impinges the loose pulley, and in turn the clutch member thereof slides the shiftable element on the stub shaft. This action simultaneously engages the various clutch members, with the result that the power from the loose pulley is transmitted to the shaft of the stitching mechanism. Immediately the shiftable element commences to rotate, the pinion rotates the gear wheel 46, which of course increases the tension of the spring 50. Movement of the gear wheel continues until the lugs 47 and 48 contact with the bevelled peripheries 35 and 36 of the clutch members, at which time the lug 47 commences to act as a brake to retard the motion, while the lug 48 through its roller 49 commences to slide the loose pulley on the stub shaft 17, and thereby disconnect the power from the shiftable element. The disengagement of the clutch 31, is just a trifle in advance of the close ap-

lication of the friction of lug 47 on its cooperating surface, therefore as soon as the power is disconnected, the brake commences to retard the momentum of the stitching mechanism and as the gear wheel cannot rotate any further, the number of stitches is not only limited but the needles are stopped at a point above the presser foot and positioned for the next operation, the proportion 10 of the parts, particularly the presser foot, being such that the first leg of the spear point terminates at the center of the cord which was previously used as a guide in connection with the edge of the presser foot. 15 Lateral movement of the loose pulley 32 on the stub shaft 17, causes the teeth on the members of the positive clutch to engage, this engagement being maintained until pressure on the treadle is released, al- 20 though the members of the friction clutch 31 are separated at the time the lug 48 contacts with the clutch member 30. Hence, while the power is thrown off the mechanism, the positive clutch holds the stitching 25 mechanism in stopped position through the lug 47 and the gear wheel 46. It therefore follows that when the lugs 47 and 48 come into operative relation with the clutch mem- 30 bers, they serve to disconnect the power, ap- 35 ply the brake on the stitching mechanism after the power is disconnected, and posi- tively stop the stitching mechanism at a predetermined point, and hold same in this position until the treadle is released to per- 40 mit the parts to return to normal position. It will of course be understood that the brake element 47 is forced into contact with the surface 36 of the clutch element 24 under the driving power of the motive mech- 45 anism of the sewing machine, and that the frictional cooperation between these parts would necessarily require substantially a power of similar force to move the gear wheel 46 in the opposite direction to 50 break the frictional contact, or in other words relieve the braking action. The spring 50 is obviously insufficient to exert this power, and hence the wheel 46 will remain in braking position until pressure on the treadle is released, at which time the clutch element 32 moves laterally, relieving pressure on the spring 38, and the clutch element 24 is thereupon disengaged from the 55 cooperating clutch element 21 by force of the spring 29. The clutch element 24 then moves laterally and is wholly free, where- upon the spring 50 will restore the parts to normal position.

When the lugs 47 and 48 impact with the bevelled surfaces of the clutch members, the blow is quite considerable. The strain on the parts however, is relieved by the buffer springs at the bottom of the arm. That is to say, because of the gear wheel be- 60 ing mounted on the arm, and the fact that

the latter is hung on the hub of one of the clutch members and swings in an arc, the arm and gear being locked together, they both rock as a unit, the springs absorbing the shock, and subsequently return the parts to the position when stopped by the impact of the lug with the clutch member. 70

One leg of the spear having been thus completed, the operator releases the treadle, the presser foot is elevated, and the glove is adjusted for the other leg of the spear. In this adjustment, the cord a , is turned at right angles to the inclined edge 10 of the guide, and the final stitching of the leg previously completed, that is, the juncture of that leg of the spear and the cord, is accurately positioned beneath the needles by sighting through the opening 10^a, this position being plain from Fig. 11. The stitching of the second leg of the spear is then completed, this line of stitching starting at the cord and continuing for a number of stitches determined by the control mechanism to complete the second leg of the spear. During this stitching, the cord a , is main- 80 tained at proper angles to the edge 10 of the guide, and hence the line of stitching of this second leg will be at exactly the same angle to the cord as is the first leg, and the number of stitches in each leg of the spear will be exactly identical. After position- 90 ing the glove for the stitching of the second leg of the spear, the presser foot is lowered, the treadle is depressed, and the parts are operated as described in the formation of the first leg of the spear, the stitching mechanism stopping when the leg reaches the desired length as shown in Fig. 11^a. 100

Thus, as described, the legs of the spears are formed at the proper or predetermined angle to each other, and each contains the same number of stitches and therefore all the legs are of the same length. It is evi- 105 dent however, that the legs of the spears may be made at any predetermined angle with reference to the cords. 110

After the legs of the spear are finished, if perchance either of them require an additional stitch or two, or mending is neces- 115 sary, the stitching mechanism is entirely disconnected from the power shaft and the operator can manually turn the hand wheel and thereby make the desired number of additional stitches or mend the stitching without in any way affecting a subsequent operation. 120

Spear points made in accordance with this invention are all uniform, both in length and angle, which lends neatness and beauty to the final product. In addition to the uniformity of the product, the cost of production is materially reduced and the speed in manufacture is correspondingly increased. 125 130

It may be found desirable to add a third or even more legs to the spear. In the event of the third leg, it is usually applied at the end of the cord and in line therewith as at *c*, Fig. 15. In arranging the glove for the stitching of this leg, the terminal of the cord *a*, is aligned substantially with the edge 10 of the guide with the cord extended in the line of stitching. As previously stated, the end of the cord will then be positioned from the sight opening 10^a a distance corresponding accurately to the distance permitted the stitching operation by the automatic control means. If desired, the cord in its original position for this third leg may be further and possibly more accurately positioned by maintaining one of the legs of the spear already formed at right angles to the edge 10 of the guide, this will insure that the third leg of the spear is in line with the cord. The operation of the control for the stitching mechanism will of course be affected after the glove back is positioned for this third leg and the presser foot has been lowered to permit stitching.

So far as I am aware, spear points on gloves have been made in a slow and rather guess work fashion, no attempt having been made to guide the location of the legs or regulate the number of stitches required in the legs to make them uniform. Manufacturers depend today upon the skill and intuition of the operators in making spear points on gloves, which, as above stated, results in defective and irregular production. By my method and machine, all the spear points on a glove are uniform in formation and accurate in length and angle.

If desired, the double bevelled edge of the presser foot can be employed, one edge being for one leg of the spear while the other edge can be used for the opposite spear leg.

It will be obvious that the presser foot may be formed with other edges and slots to permit making three or four or more points on a glove back.

The parts are so constructed as to make it possible to attach the improvement to machines now in use, by simply removing the ordinary hand wheel, applying my construction, and securing the frame for the supporting arm on the table of the machine.

Of course, the presser foot on the machine should be changed to be in accord with the construction described.

It has been heretofore stated that ordinarily the length of the leg of the spear point will be equal to the distance between the sight opening 10^a and the inclined edge 10 of the guide in the line of stitching, and under these circumstances the cord in the formation of the first leg will be aligned with the inclined edge of the guide as shown

in Fig. 10. However, as the automatic means for controlling the number of stitches is adjustable in adapting the same for a greater or less number of stitches than that required for the predetermined distance 70 above referred to, it is apparent that with such greater number of stitches for example, the cord in its initial positioning as indicated in Fig. 10, will be arranged in parallelism with the inclined edge of the 75 guide but spaced therefrom to provide for the greater length of spear point leg determined upon. Thus with the use of the guide and the proper control of the automatic stitching mechanism, the length of the 80 leg of the spear point may be regulated as desired, and this without necessitating the change of the guide or presser foot for such different lengths.

Claims:

85

1. The herein described method of stitching spear points on gloves to form such points of uniform lengths and angularity with respect to the cords from which they extend, consisting in positioning the glove 80 in the sewing machine by arranging one of the cords in predetermined relation to a guide to thereby determine the angularity of the stitching of the particular spear point leg with relation to the cord from which it 95 extends, automatically limiting the number of stitches of such spear point leg in the subsequent stitching operation.

2. The herein described method of stitching spear points on gloves having cords, 100 consisting in first determining the angularity of the spear point leg to be stitched with relation to the cord from which it extends by positioning the glove to register the cord with a guide, and automatically 105 limiting the number of subsequent stitches in the formation of such leg while maintaining the initial relation of the cord and guide.

3. The herein described method, consisting in placing the glove for stitching with one of the cords in predetermined relation to an edge guide to thereby determine the angularity of subsequent spear point stitching to said cord, and automatically limiting 115 such subsequent stitching to a predetermined number of stitches while maintaining the initial relation of the cord and guide.

4. The herein described method of providing spear points for gloves having cords, 120 consisting in providing a cord guide having an edge of that angularity to the line of stitching corresponding to the angularity of the spear point legs to the cord from which they extend, positioning the glove to arrange one of the cords in predetermined relation to the edge of the guide, stitching the spear point leg while maintaining the guided relation of the glove cord to the edge of the guide, and automatically stop- 125 130

ping the stitching operation following a predetermined number of stitches.

5. The herein described method, consisting in providing a guide having an edge at an angle to the normal line of stitching, positioning the glove with the initial point of stitching beneath the needle and one of the cords in predetermined relation to said guide, and stitching a spear point leg with 10 a predetermined number of stitches, changing the position of the glove to arrange the previously guided cord in a different relation to the guide, and stitching the second leg of the spear point with an exactly identical number of stitches as in the first leg.
6. The herein described method, consisting in utilizing a cord to which the spear point is to be applied as a guide, arranging this guide cord in predetermined relation to 20 an edge guide to define the angularity of the particular spear point leg being stitched to the cord from which it extends, and automatically limiting the stitching of both legs of the spear point to an identical number 25 of stitches.
7. The herein described method, consisting in utilizing a cord of a glove back to which spear points are to be applied for cooperation with an edge guide to determine 30 the angularity of both legs of the spear point with respect to that cord, the cord in one instance being aligned with the edge

guide and in the other instance being at right angles to said edge guide, and stitching the respective legs of the spear toward 35 the cord in the formation of the first leg and from the cord in the formation of the second leg, the said stitching being automatically limited in both legs to the same number of stitches.

8. In an apparatus for controlling the application of spear points to gloves having cords, comprising a guide having an edge at that angle to the normal line of stitching corresponding to the angle between each 45 spear point leg and the cord from which it extends, combined with means to limit the stitching operation of the spear point leg to a predetermined number of stitches.

9. In an apparatus for controlling the application of spear points to gloves having cords, comprising a guide having an edge at that angle to the normal line of stitching corresponding to the angle between each 50 spear point leg and the cord from which it extends, combined with means to limit the stitching operation of the spear point leg to a predetermined number of stitches, said 55 guide being formed with a needle opening serving additionally as a sight opening for ascertaining if the spear point leg terminates at and joins the cord.

In testimony whereof I affix my signature.
WILL R. GEARY. [L.S.]
